[57] CLAIM

The ornamental design for a lid removing tool, substantially as shown and described.

DESCRIPTION

FIG. 1 is a top plan view of the lid removing tool design;

FIG. 2 is a bottom view of the design;

FIG. 3 is a front view in elevation of the design;

FIG. 4 is a rear view in elevation of the design;

FIG. 5 is a right side view of the design; and

FIG. 6 is an opposite view of the design of the present invention.
